DISPLAY STAND COLUMN

Filed April 27, 1929

INVENTOR,
Charles W. Joham;

BY

J. E. Maynard, ATTORNEY.

UNITED STATES PATENT OFFICE.

CHARLES W. JOHAM, OF LOS ANGELES, CALIFORNIA, ASSIGNOR TO STERN, JOHAM AND GROSSMAN, INC., A CORPORATION OF CALIFORNIA.

DESIGN FOR A DISPLAY-STAND COLUMN.

Application filed April 27, 1929. Serial No. 31,028. Term of patent 3½ years.

To all whom it may concern:

Be it known that I, CHARLES W. JOHAM, a citizen of the United States, and resident of Los Angeles, California, have invented a new, original, and ornamental Design for a Display-Stand Column, of which the following is a specification, reference being had to the accompanying drawing, forming a part hereof.

Figure 1 is a side elevation of the column showing my new design.

Figure 2 is a plan; the stem being in cross-section to illustrate its shape.

I claim:

The ornamental design for a display stand column, substantially as shown.

CHARLES W. JOHAM.
